US0D1077680S

(12) **United States Design Patent** (10) **Patent No.:** **US D1,077,680 S**
(45) **Date of Patent:** **** Jun. 3, 2025**

(54) **MOTOR VEHICLE**

(71) Applicant: **VOLKSWAGEN AKTIENGESELLSCHAFT, Wolfsburg (DE)**

(72) Inventors: **Andreas Mindt, Wolfsburg (DE); Arnaldo Cruzeiro Silva, Jr., Wolfsburg (DE); Christian Lesmana, Wolfsburg (DE)**

(73) Assignee: **VOLKSWAGEN AKTIENGESELLSCHAFT, Wolfsburg (DE)**

(**) Term: **15 Years**

(21) Appl. No.: **29/917,167**

(22) Filed: **Nov. 17, 2023**

(30) **Foreign Application Priority Data**

Jul. 13, 2023 (DE) 40 2023 100 479.9
(51) **LOC (15) Cl.** **12-08**

(52) **U.S. Cl.** ..... **USPC D12/92**
